ENGINE STARTING MECHANISM

Raymond P. Lansing, Montclair, N. J., assignor to Eclipse Aviation Corporation, East Orange, N. J., a corporation of New Jersey

Application January 6, 1930, Serial No. 418,959

18 Claims. (Cl. 123—179)

This invention relates to starting devices for internal combustion engines and more particularly to starters of the inertia type.

One of the objects of the present invention is to provide a novel engine starter of the type having a small high-speed inertia member which is characterized by its simplicity, compactness and cheapness of manufacture.

Another object is to provide a novel starter of the inertia type which is completely self-contained and every element of which is mounted on and carried by a rotatable member of the engine to be started.

A still further object is to provide an inertia type engine starter which is especially well adapted for use with engines of the outboard type commonly employed to propel small boats because of its size and low manufacturing cost and the fact that it may be mounted as a unit on such an engine without requiring a change in the design thereof.

Another object is to provide a novel engine starter wherein the energy stored in a rapidly rotating inertia member may be transferred to a member of the engine to be started through a novel arrangement of parts which eliminates the usual requirement of this type of starter for a fixed member for absorbing the reaction due to starting.

Still another object is to provide a novel engine starter of the inertia type which is characterized by the fact that after the engine has attained a predetermined speed under its own power, the elements of the starting mechanism are held against further rotation independent of the engine member and thereafter constitute a flywheel for said engine.

The above and other objects will appear more fully in the detailed description of the invention which follows. In the drawing, wherein like reference characters refer to like parts in the different views,

Fig. 1 is a side elevation, in section, of one embodiment of the present invention; and

Fig. 2 is a top plan view of the parts shown in Fig. 1.

The embodiment of the invention illustrated is particularly adapted for use in starting outboard motors, but is not limited to such use, and comprises an inertia member, together with means for actuating and storing energy therein, mounted on and housed within a rotatable member of the engine to be started, said inertia member and actuating means being adapted for rotation independently of said engine member prior to the

starting thereof, but also designed for engagement and rotation with said member after the engine has been started and has attained a predetermined speed.

In the form shown, the engine to be started is provided with a rotatable member 3, which, if desired, may be in the form of a flywheel drivably secured to a shaft 4 by any suitable means such as a key 5 and nut 5^a. Shaft 4 may be the crankshaft of the engine or an extension thereof. Rigidly attached, as by means of screws 6, to the upper face of member 3 is a casing member 7 which is designed to house and support a portion of the inertia actuating means. A cover plate 8 closes the upper end of casing member 7 and is secured thereto by any suitable means such as screws 9. Cover plate 8 is provided with a central opening 10 surrounded by a flange 11 through which extends a vertical shaft 12. A ball bearing 13 is mounted in flange 11 for rotatably supporting said shaft, said bearing being retained in flange 11 by an annular retaining ring 14 which is secured to cover plate 8 by any suitable means such as a plurality of pins 15 which are fitted with washers and cotter pins. The lower end of shaft 12 is journaled in a recess 16 formed in the upper end of shaft 4, a suitable bushing 16^a being fitted in the recess.

Shaft 12 constitutes the driving or cranking member of the means for actuating and storing energy in the inertia member. To this end said shaft is provided with an enlarged portion 17 adjacent its lower end to which is drivably secured in any suitable manner, as by splines, a driving gear 18 which meshes with a pair of diametrically disposed pinions 19, it being understood that a larger number of such pinions 19 may be employed if desired. As shown, each pinion 19 is formed as an integral part of a shaft 20 which is rotatably supported in a boss 21 formed in and projecting from the interior surface of casing member 7. A suitable bushing 22 is fitted within each boss 21, and shaft 20 is held against longitudinal movement therewithin by means of a nut 23 threaded on the lower end of said shaft. The latter carries, at its upper end, a spur gear 24 which meshes with a pinion 25 that is formed integral with the lower end of a sleeve shaft 26 which surrounds the upper portion of, and is freely rotatable relative to shaft 12. Extending laterally from the upper end of shaft 12 is a pair of projecting pins 27 which are adapted to be engaged by a suitable hand-crank (not shown) for the purpose of rotating said shaft. It will thus be seen that any rotation of shaft 12, through the medium of a

hand-crank and pins 27 will be transmitted through gear 18, pinions 19, gears 24, and pinion 25 to sleeve shaft 26, and due to the ratios of the gears employed shaft 26 will rotate at a much higher speed than shaft 12.

The inertia member of the starting mechanism is adapted to be operatively connected to shaft 26 and driven thereby through novel friction clutch means. As shown, said inertia member 10 comprises a pair of annular rim member 28 which are suitably secured to the opposite faces of a disk or web 29 as by rivets 30. Web 29 is rotatably supported on sleeve shaft 26 but is adapted to be drivably connected thereto by means of a friction clutch comprising a pair of disks 31 and 32, between which web 29 extends. Lower disk 31 may be drivably connected to sleeve shaft 26 by any suitable means and is held against longitudinal movement thereon by the inner race of bearing 13. Upper disk 32 is also drivably secured to sleeve shaft 26 as by splines and is resiliently urged into clutching contact with the upper face of web 29 by means of a spring 33. The upper end of the latter bears against a flanged portion 34 of a nut 35 which is threaded onto the upper end of sleeve shaft 26 and held in adjusted position by a lock nut 36. The torque transmitted by clutch 29, 31, 32 may be readily varied by adjustment of nut 35. If desired, the clutch mechanism 20 and flywheel may be enclosed in a light, metal housing retained in position by the same screws 9 that secure plate 8 to casing member 7.

The mechanism above described constitutes means for storing up energy to be subsequently used, at the will of the operator, for cranking and starting the engine. Novel means are provided for operatively connecting the flywheel, after the desired amount of energy has been stored therein, to the member of the engine to be started. For 35 this purpose, the hub of gear 18 is provided with an enlarged portion 38 to which is splined a longitudinally movable, jaw clutch member 39 adapted for engagement with a similar member 40 which is rigidly secured to engine member 3 as by rivets 41. A spring 42, interposed between the upper end of shaft 4 and the bottom face of an internal flange 43 carried by clutch member 39, normally maintains the latter out of driving engagement with member 40.

50 A meshing rod 44 which extends through the bore of shaft 12 is provided for moving jaw member 39 into engagement with jaw member 40 at the will of the operator. Rod 44 carries, adjacent its lower end, a pair of projecting pins 45 which extend through elongated radial slots 46 formed in shaft 12, and which engage the upper surface of flange 43 of jaw member 39.

In operation, the hand crank is engaged with pins 27 and shaft 12 is rotated until the flywheel 55 is brought up to a speed sufficient to store the desired amount of energy for use in starting the engine. It will be noted that rod 44 is not accessible when the hand crank is engaged with cranking shaft 12, and that shaft 4, casing 7, and bosses 21 are stationary during the time that energy is being stored in the inertia member. When the hand crank has been brought to a speed of approximately 50 R. P. M. for example, the crank 60 is disengaged from pins 27 and meshing rod 44 is moved downwardly by hand whereupon jaws 39 and 40 are engaged, and the resultant reaction, due to the tendency to stop gear 18 from rotating, is exerted upon casing member 7 of engine member 3 through the medium of shafts 20 and bosses 21, and the casing 7 and engine 75 25 and bosses 21, and the casing 7 and engine

members 3, 4 are rotated, whereby the engine is cranked and started.

Should the engine backfire during the starting operation, the starter parts are fully protected against damage by the friction clutch 31, 29, 32. When the engine operates under its own power and tends to drive clutch member 39, the inclined teeth of said jaw clutch members and spring 42 are effective to move said clutch member and rod 44 to normal or non-engaging position. 80 85

The reduction of weight is often a question of primary importance in engine installations of the type disclosed herein and the present invention embodies novel means for drivably connecting the starter elements to the engine crank-shaft; after the engine has started under its own power and attained a predetermined speed of rotation, whereby said elements act as a flywheel for the engine and the usual flywheel may be 90 eliminated or greatly reduced in weight. To this end, centrifugally actuated means are provided on the casing, which are effective upon rotation of the engine member at a predetermined speed to engage the inertia member or flywheel 95 and cause the same, together with the other elements of the mechanism, to rotate in unison with the engine shaft. As illustrated, the centrifugal means comprise a pair of pawls 47 which are pivotally mounted on the upper ends 100 of pins 15 and which are normally maintained in disengaged position (shown by the dotted lines in Fig. 2) by suitable resilient means such as springs 48, one end of each of which passes through a slot in the upper end of pin 15, while the other end is secured to pawl 47 by any suitable means 105 such as soldering.

When the engine starts under its own power and the speed of engine member 3 increases to a predetermined point, pawls 47 fly out under centrifugal force and engage depressions 49 which are formed in the inner periphery of one of the rim members 28 of the flywheel, thus forming a driving connection between the engine member 3 and the inertia member whereby the entire 115 starting mechanism revolves with the engine member 3 as a unit, its mass thus augmenting 120 that of member 3 to form a flywheel for the engine.

There is thus provided a novel engine starter 125 of the inertia type which is simple and rugged in structure, inexpensive to manufacture, and efficient in operation. It is especially well adapted for use with small engines, such as those of the outboard type, because of its compactness and 130 light weight. Since it is a self-contained unit it may be easily attached to any engine, and requires no external supporting means, the whole unit being carried by a rotating member of the engine. A further feature of the present invention 135 which makes it particularly well suited to engine installations of the outboard type is that the mechanism performs the dual function of starter and engine flywheel. Simple and efficient means are provided to protect the parts against 140 damage from a "backfire".

The invention is not limited to the specific form or use described and illustrated in the drawing, but is capable of a variety of mechanical embodiments and uses, and reference is therefore to be had to the appended claims for a definition of the 145 limits of the invention.

What is claimed is:

1. In a starter for internal combustion engines of the type embodying a high speed inertia mem- 150

- ber, an engine member to be rotated, means for drivably connecting said inertia member and engine member including a casing enclosing said inertia member rigidly connected to the engine member, and means operable after the engine starts under its own power for rotating the starter elements in unison with the engine member. 80
- 5 member for rotation therewith continuously during the operation of the engine, and means for storing energy in the flywheel, and means for holding said casing stationary during the energy storing operation. 85
- 10 2. In mechanism of the class described, a rotatable member of an engine to be started, a casing rigidly secured thereto, an inertia member housed within said casing and mounted for rotation relative thereto, means for actuating said inertia member and storing energy therein including a cranking shaft, a gear train, and a friction clutch, and a member drivably secured to an element of said gear train and adapted for engagement with the engine member at the will of the operator. 90
- 15 3. In an engine starter, the combination of a rotatable engine member, a flywheel mounted on said engine member and adapted for independent rotation relative thereto, means for rotating and storing energy in said flywheel, means for transferring the energy thus stored in said flywheel to the rotatable engine member for starting the same, and means effective upon the attainment by said rotatable engine member of a predetermined speed for positively engaging said flywheel with said engine member so as to prevent further relative rotation between any of the elements of the combination, all of the elements of said combination being carried by said rotatable engine member. 95
- 20 4. In apparatus of the class described, an engine member to be started rotating, a casing member secured to said engine member, a flywheel mounted within said casing member and adapted for independent rotation relative thereto, means including a gear train for rotating said flywheel and storing energy therein, means for engaging one element of said gear train with the engine member at the will of the operator, and centrifugal means carried by said casing member for positively engaging said flywheel when said casing member attains a predetermined speed of rotation. 100
- 25 5. In mechanism of the class described, a rotatable member of an engine to be started, a casing rigidly secured thereto, an inertia member housed within said casing and mounted for rotation relative thereto, means for actuating said inertia member and storing energy therein, and a member drivably secured to an element of said actuating means and adapted for engagement with the engine member at the will of the operator. 105
- 30 6. In combination with a member of an engine to be started, a flywheel in which energy is adapted to be stored for starting the engine, means for rotating the flywheel, means for drivably connecting the flywheel and engine member for rotation of the latter by the former at a substantially reduced speed, and means mounted on the engine member and rotatable therewith for supporting the flywheel and said first and second named means. 110
- 35 7. In combination with a rotatable member of an engine to be started, a flywheel in which energy is adapted to be stored for starting the engine, said flywheel being adapted for rotation therewith during normal operation, a supporting casing for the flywheel rigidly attached to the engine member, means for drivably connecting the flywheel and engine member for rotation of the latter by the former at a substantially reduced speed, and means for rotating the flywheel relative to the casing to store energy therein. 115
- 40 8. In combination with a rotatable member of an engine to be started, a supporting member rigidly attached to said engine member, a flywheel in which energy is stored for starting the engine, said flywheel being mounted on the supporting member and adapted for rotation relative to the supporting member during the starting operation, means mounted on the supporting member and operable during the starting operation to drivably connect the flywheel and supporting member, and means for connecting 120
- 45 9. In apparatus of the class described, an engine member to be started rotating, a casing member secured to said engine member, a flywheel mounted within said casing member and adapted for independent rotation relative thereto, means including a gear train for rotating said flywheel and storing energy therein, means for engaging one element of said gear train with the engine member at the will of the operator, and centrifugal means carried by said casing member for positively engaging said flywheel when said casing member attains a predetermined speed of rotation. 125
- 50 10. In mechanism of the class described, a rotatable member of an engine to be started, a casing rigidly secured thereto, an inertia member housed within said casing and mounted for rotation relative thereto, means for actuating said inertia member and storing energy therein, and a member drivably secured to an element of said actuating means and adapted for engagement with the engine member at the will of the operator. 130
- 55 11. In mechanism of the class described, a rotatable member of an engine to be started, a casing rigidly secured thereto, an inertia member housed within said casing and mounted for rotation relative thereto, means for actuating said inertia member and storing energy therein including a gear train, and a member drivably secured to an element of said gear train and adapted for engagement with said engine member at the will of the operator. 135
- 60 12. In apparatus of the class described, an engine member to be started rotating, a casing member secured to said engine member, a flywheel mounted within said casing member and adapted for independent rotation relative thereto, means including a gear train for rotating said flywheel and storing energy therein, means for engaging one element of said gear train with the engine member at the will of the operator, and means carried by said casing member for positively engaging said flywheel when said casing member attains a predetermined speed of rotation. 140
- 65 13. In combination with a rotatable member of an engine to be started, a supporting member rigidly attached to said engine member, a flywheel in which energy is stored for starting the engine, said flywheel being mounted on the supporting member and adapted for rotation relative to the supporting member during the starting operation, means mounted on the supporting member and operable during the starting operation to drivably connect the flywheel and supporting member, and means for connecting 145
- 70 14. In apparatus of the class described, an engine member to be started rotating, a casing member secured to said engine member, a flywheel mounted within said casing member and adapted for independent rotation relative thereto, means including a gear train for rotating said flywheel and storing energy therein, means for engaging one element of said gear train with the engine member at the will of the operator, and means carried by said casing member for positively engaging said flywheel when said casing member attains a predetermined speed of rotation. 150

the flywheel and engine member whereby the flywheel and engine member rotate in unison.

14. In combination with a rotatable member of an engine to be started, a flywheel in which energy is stored for cranking said engine member, said flywheel being adapted for rotation during the starting operation, means operable during the starting operation to drivably connect the flywheel and engine member, and centrifugally actuated means for connecting the flywheel and engine member whereby the flywheel and engine member rotate in unison.

15. In a mechanism of the class described, a member to be started rotating, a flywheel mounted for rotation independently of said member, means for accelerating said flywheel including a gear train, at least one gear element of which is disposed within said member, bearing means integral with said member for rotatably supporting said gear element, said bearing means and member being stationary as said gear element rotates with said flywheel accelerating means, and means for drivably connecting said gear train with said member to be started rotating, thereby setting up a force tending to cause said bearing means to move with said gear element about a common axis and thus cause said member also to rotate about said axis.

16. In a mechanism of the class described, a member to be started rotating, a flywheel mounted for rotation independently of said member, means for accelerating said flywheel including a pair of diametrically disposed pinions mounted

35. on a flywheel accelerating means, and means for drivably connecting said pinions with said member to be started rotating.

40. In a mechanism of the class described, a member to be started rotating, a flywheel mounted for rotation independently of said member, means for accelerating said flywheel including a pair of diametrically disposed pinions mounted

45. on a flywheel accelerating means, and means for drivably connecting said pinions with said member to be started rotating.

50. In a mechanism of the class described, a member to be started rotating, a flywheel mounted for rotation independently of said member, means for accelerating said flywheel including a pair of diametrically disposed pinions mounted

55. on a flywheel accelerating means, and means for drivably connecting said pinions with said member to be started rotating.

60. In a mechanism of the class described, a member to be started rotating, a flywheel mounted for rotation independently of said member, means for accelerating said flywheel including a pair of diametrically disposed pinions mounted

65. on a flywheel accelerating means, and means for drivably connecting said pinions with said member to be started rotating.

70. In a mechanism of the class described, a member to be started rotating, a flywheel mounted for rotation independently of said member, means for accelerating said flywheel including a pair of diametrically disposed pinions mounted

75. on a flywheel accelerating means, and means for drivably connecting said pinions with said member to be started rotating.

for planetary movement within said member, bearing means integral with said member for rotatably supporting said pinions, said bearing means and member being stationary as said pinions rotate with said flywheel accelerating means, and means for drivably connecting said pinions with said member to be started rotating, thereby setting up a force tending to cause said bearing means to move with said pinions about a common axis and thus cause said member also to rotate about said axis.

17. In combination with a rotatable member of an engine to be started, an inertia starter mounted on the rotatable member, said starter including a reduction gear train and a high speed flywheel driven thereby, means for storing energy in said flywheel through said gear train, and means supported by said member and including said gear train for drivably connecting said flywheel and member after energy has been stored

80

85

90

95

18. In combination with a rotatable member of an engine to be started, an inertia starter including a gear train having every element thereof mounted on the rotatable member, said starter also including a high speed flywheel, and means for storing energy in said flywheel through said gear train, and subsequently operable means acting independently of said flywheel for drivably connecting said flywheel and engine member.
